AUTOMOBILE WHEEL

Henry James Clary, Orange, Calif. (16427 S. Avalon Blvd., Gardena, Calif. 90248), and Delmer D. Scott, Los Angeles, Calif. (5020 Gloria Ave., Encino, Calif. 91316)

Filed Aug. 28, 1973, Ser. No. 392,195

Term of patent 14 years

Int. Cl. D12—16
U.S. Cl. D12—205

FIG. 3.

FIG. 4.

FIG. 1 is a front elevational view of an automobile wheel showing our new design;

FIG. 2 is a cross-sectional view taken on the line 2—2 of FIG. 1;

FIG. 3 is a rear elevational view;

FIG. 4 is a side elevational view thereof.

I claim:

The ornamental design for an automobile wheel, as shown.
